PIPE AND MUFFLER CUTTER

Walter E. Lindley and Mack M. Martin, Houston, Tex.,
assignors to Muffler Products Corporation, Houston,
Tex., a corporation of Texas

Application October 1, 1956, Serial No. 43,152

Term of patent 14 years

(Cl. D54—13)

Fig. 1 is a plan view of a pipe and muffler cutter showing our new design;

Fig. 2 is a side elevation taken from the right of Fig. 1;
Fig. 3 is a view taken from the top of Fig. 1; and
Fig. 4 is a transverse section on line 4—4 of Fig. 1.

We claim:

The ornamental design for a pipe and muffler cutter,
as shown.
